PLASTICIZER AND MOISTURE RETENTIVE COMPOSITION FOR PAPER AND PAPER CONTAINING IT

Louis Lang and Ronald J. Baird, Philadelphia, Pa., assignors to The National Sugar Refining Company, New York, N. Y., a corporation of New Jersey

No Drawing. Application February 8, 1950,
Serial No. 143,166

16 Claims. (Cl. 106—162)

1

Our invention relates to a composition applicable to paper in the process of making same to plasticize the paper and make it sufficiently moisture retentive to prevent its drying to brittleness and to the paper so prepared.

Heretofore glycerine or compositions containing glycerine have been used in the making of paper to enable the paper to retain moisture to a sufficient extent to render it pliable and flexible, a small amount of the glycerine, which has a tendency to absorb and hold moisture, being retained in the finished paper.

Our present invention relates to a composition having excellent water retentive properties, which may be made cheaply and without limitation as to the quantity available and which, therefore, serves as an excellent lubricant and moisture retaining agent for paper.

The composition of our invention comprises an admixture, preferably as a concentrated solution, of a sugar, urea, and a glycoside, or a cyclic acetal of a sugar or glycoside. The glycoside may be, for example, an alkyl glycoside such as methyl glycoside, ethyl fructoside, etc., and the acetal may be monoisopropylidene glucose, diethylidene fructose, etc. A mixed acetal glycoside such as, for example, a cyclic acetal of an alkyl glycoside such as monoisopropylidene ethyl fructoside may be used, and mixtures of acetals and glycosides may also be used. The aldehydes and ketones from which the acetals are derived, and the alcohols from which the glycosides are derived, have not more than three carbon atoms.

Such acetals are soluble in water and form with the sugar and urea a composition or mixture which may be taken up in very small amount by the paper pulp in the manufacture of paper and be retained on the fibers. The quantity thus retained will be sufficient to prevent loss of all moisture by the paper without being sufficient to render the paper too absorptive of moisture under normal atmospheric conditions.

The composition may be used to advantage with all types of paper, but more particularly with glassine paper to render the latter grease resistant and sufficiently moisture retentive.

The acetals or glycosides may be formed respectively by reacting a suitable sugar, such as dextrose or invert sugar with an aldehyde, ketone or alcohol of not more than three carbon atoms in the presence of a suitable acid catalyst.

2

Examples of the aldehydes, ketones and alcohols suitable for this purpose are: formaldehyde; paraformaldehyde (polyoxymethylene); trioxane; acetaldehyde; paraldehyde; acetone; methanol; ethanol; isopropanol and normal propyl alcohol. Any combination of the above may be used as well as any individual of the above group.

The acid catalyst may be, for example, phenol-sulfonic acid or toluosulfonic acid or sulfuric acid. The acetal produced from any of the above materials is a water soluble compound and may be dissolved with urea and the sugar to produce the composition of our invention.

15 The relative proportions of the urea to dextrose or other sugar may be in the ratio of anywhere from 1:9 to 9:1, and the acetal or glucoside may be present in the final solution in amounts between 1% and 50%.

15 Examples of the manner of making the composition are as follows:

Example 1

25 4 kg. of powdered sugar (i. e. sucrose) are mixed with 2 kg. of powdered anhydrous magnesium sulfate. In a separate vessel 50 ml. of concentrated sulfuric acid are mixed with 6 liters of acetone. All these ingredients are mixed together and agitated slowly and continuously for two days. 60 grams of light magnesium oxide powder are then added and the agitation is continued until the liquid is no longer acid to litmus.

30 The liquid is filtered off, the residue washed with acetone and the combined filtrate and washings concentrated to give 1.63 kg. of acetone derivative.

35 The above compound may be admixed in aqueous solution with urea and a sugar in the proportions indicated above to form the paper plasticizer. The proportions may be adjusted to give any degree of moisture retention and grease resistance or to suit any conditions of paper manufacture. Preferably it is made of 75% of solids and 25% water.

Example 2

45 210 grams of phenol sulfonic acid (mixed ortho and para isomers) are dissolved in a mixture of 14 liters acetone and 14 liters ethyl alcohol (95% S. D. A. formula #23-A). The mixture 50 is stirred slowly with a mechanical stirrer with

large paddles in a jacketed copper kettle provided with reflux condenser, while 35 lbs. of fine granulated sugar (i. e. sucrose) are added. Steam or hot water is then turned on in the jacket to maintain a refluxing temperature of the reacting mixture until all the sugar is dissolved (about 8 hours). The product is then stirred with a suspension of 310 grams of calcium carbonate in 1 liter of water until the pH is above 6. The product is filtered and concentrated to a soft resinous consistency by evaporation of the solvents in a rapid evaporator.

The above compounds comprising mixed acetal-glucoside may then be mixed with a sugar, such as dextrose, and urea to the desired solutions and concentration.

Example 3

In the equipment of Example 2 are reacted in a similar way 35 lbs. of sugar with 14 liters of acetone, 5 liters of paraldehyde and 160 grams of phenol sulfonic acid. The mixture is neutralized with 24 grams of calcium carbonate in 1 liter of water, filtered and concentrated as in Example 1.

Example 4

In a similar way is prepared a resinous material from 50 lbs. of sugar, 8.5 liters of acetone, 8.5 liters ethyl alcohol (95%), 1.7 liters of paraldehyde, 115 grams of toluene sulfonic acid. The mixture after reaction is neutralized with powdered sodium bicarbonate at 50° C., filtered and concentrated as above.

Example 5

400 grams of sugar, 300 ml. of paraldehyde (a trimer of acetaldehyde) and 2.5 grams of toluene sulfonic acid are heated together on a hot water bath in a flask provided with agitator and reflux condenser during 5½ hours. All of the sugar dissolves. After cooling 3 grams of calcium carbonate are added. The mixture is again heated for a short time, filtered and concentrated to yield 553 grams of a clear, water-soluble resinous material which is combined with urea and dextrose as in previous examples.

Example 6

In a similar way are reacted 484 grams of sugar, 145 grams of paraformaldehyde, 121 ml. of paraldehyde and 2.4 grams of toluene sulfonic acid. The reaction time is 2 hours. The product is neutralized by heating with powdered sodium bicarbonate and concentrated to yield 652 grams of a product which is mixed with urea and dextrose as in previous examples.

It will be understood that the above are given merely by way of example and other acetals of aldehydes and ketones and glycosides of alcohols having three or less carbon atoms may be similarly formed and mixed with suitable sugars and urea to form the paper lubricant and moisture retention medium of our invention.

Wherever "a sugar" or "the sugar" is mentioned above, it is understood that it is used in a generic sense.

Having described our invention, what we claim is:

1. A plasticizer and moisture retentive composition for paper, the essential paper plasticizing and moisture retentive constituents of which consist essentially of (I) a sugar and (II) urea, in proportions between one of the sugar to nine of urea and one of urea to nine of the sugar, and (III) a water-soluble cyclic acetal of a sugar in

an amount from one to fifty percent by weight of the composition and with under four carbon atoms in the alkylidene group.

5 2. The composition as claimed in claim 1, wherein the alkylidene group has three carbon atoms.

3. The composition as claimed in claim 1, wherein the cyclic acetal of a sugar is monoiso-propylidene glucose.

10 10. A plasticizer and moisture retentive composition for paper, the essential plasticizing and moisture retentive constituents of which consist essentially of (I) a sugar and (II) urea, in proportions between one of the sugar to nine of urea and one of urea to nine of the sugar, and (III) a water-soluble cyclic acetal of an alkyl glycoside with under four carbon atoms in its alkylidene group and also in the alkyl group and in an amount of from one to fifty percent by weight of the composition.

15 5. The composition as claimed in claim 4, wherein the acetal of the glycoside is monoiso-propylidene ethyl fructoside.

6. The composition as claimed in claim 4, wherein the sugar is dextrose.

25 7. A plasticizer and moisture retentive composition for paper, the essential plasticizing and moisture retentive constituents of which consist essentially of (I) a sugar and (II) urea, in proportions between one of the sugar to nine of urea and one of urea to nine of the sugar, and (III) a water-soluble alkyl glycoside with under four carbon atoms in its alkyl group and in an amount of from one to fifty percent by weight of the composition.

30 8. The composition as claimed in claim 7, wherein the alkyl glycoside is methyl glucoside.

40 9. A plasticizer and moisture retentive composition for paper, the essential paper plasticizing and moisture retentive constituents of which consist essentially of (I) a sugar and (II) urea, in proportions between one of the sugar to nine of urea and one of urea to nine of the sugar and (III) at least one water-soluble constituent of the class consisting of (a) a cyclic acetal of a sugar with under four carbon atoms in the alkylidene group; (b) an alkyl glycoside with under four carbon atoms in the alkyl group and (c) a cyclic acetal of such alkyl glycoside with under four carbon atoms in its alkylidene group; the water-soluble constituent III amounting to from one to fifty percent by weight of the composition.

45 10. The composition as claimed in claim 9, wherein the sugar is sucrose.

11. The composition as claimed in claim 9, wherein the sugar is dextrose.

12. The composition as claimed in claim 9, wherein the plasticizing and moisture retentive constituents are dissolved in water.

50 13. The composition as claimed in claim 12, wherein the plasticizing and moisture retentive constituents are dissolved in concentrated solution in water.

14. The composition as claimed in claim 12, wherein the water content is twenty-five percent.

15. A paper containing sufficient of a plasticizer and moisture retentive composition to prevent loss of all of its moisture and less than the amount that would render the paper too absorptive of moisture under normal atmospheric conditions, and in which the plasticizer and moisture retentive composition is the composition of claim 9.

70 16. A paper as claimed in claim 15, wherein the paper is glassine and said glassine is grease-

resistant because of its content of the plasticizer and moisture retentive composition.
